UNITED STATES PATENT OFFICE

2,482,597

AXIAL FLOW FAN

Irving S. Ritter, Sharon, Mass., assignor, by
mesne assignments, to Westinghouse Electric
Corporation, a corporation of Pennsylvania

Application November 26, 1946, Serial No. 712,271

1 Claim. (Cl. 230—115)

1

This invention relates to fan systems and relates more particularly to systems using axial flow fans for pressure ventilation.

By forcing large volumes of outdoor air through the passenger space of trolley cars, subway cars and other passenger vehicles, it has been found feasible to cool such vehicles during hot weather without the use of refrigeration.

Several, spaced, axial flow fans mounted in the ceilings of the vehicles along their longitudinal center lines, and arranged to blow the air downwardly into the vehicles, are generally used for such pressure ventilation.

Axial flow fans have pressure-volume characteristics such that there are dips in the characteristic curves in which the fans are unstable and in which the direction of air moved by them may be reversed by a change in fan load.

Due to changes in the number of passengers in a vehicle, the opening of doors, etc., the load on one of the fans may be such that it may become unstable and act to move air in the reverse direction to that desired. This invention provides a control which, when a fan becomes unstable, causes it to speed up so as to operate at a stable point and to deliver the air it handles, in the right direction.

An object of the invention is to reverse the direction of fluid moved by a fan when due to the fan becoming unstable, it moves the fluid in the wrong direction.

A more definite object of the invention is to speed up a fan for shifting its operating point on its pressure-volume characteristic curve when due to a change in operating condition, it moves the fluid handled by it in the wrong direction.

The invention will now be described with reference to the drawing, of which:

Fig. 1 is a diagrammatic view illustrating a fan system to which this invention applies;

Fig. 2 is a pressure-volume characteristic curve of an axial flow fan used in the system of Fig. 1, and

Fig. 3 is a diagrammatic view illustrating a pressure responsive control for speeding up one of the fans of the system for causing it to shift from an unstable operating point to a stable one.

Fig. 1 illustrates a trolley car having the three axial flow fans 5 spaced along the longitudinal center of the car and arranged to draw outdoor air into the space above the ceiling 6 of the car, and to blow the air downwardly through apertures in the ceiling, into the car.

Fig. 2 illustrates a pressure-volume characteristic curve typical of the fans of Fig. 1. There is

5 a dip 7 in the curve, the center of which is variously termed the "bubble point," the "stalling point" or the "pulsation point" of the fan. When the volume handled by the fan is shifted for any reason back into the center of the dip, it becomes unstable and tends to operate on either side of the center of the dip thus drawing or blowing air depending upon which side of the center of the dip it operates.

10 In passenger cars having fan systems such as illustrated by Fig. 1, the fans act to build up static pressures in the passenger spaces. Due to changes in the number of passengers in the cars, the assembly of a large number of passengers under one fan, or the opening of one or more of the doors of a car, it has been found that a fan which has been operating satisfactorily to blow air into the passenger space, suddenly reverses its direction of flow and takes air from the other fans and passes the air upwardly instead of downwardly.

15 According to this invention, one or more of the fans of the systems would be equipped with the control of Fig. 3 which includes the pivoted vane 8 in the airstream at the normal suction side of the fan, and which operates when the fan blows air backwardly, to move against the contact 9 to close the electric energizing circuit of the relay 10, causing the relay to pull in its armature 11. The armature 11 and the contact 12 are normally 20 in contact, forming a short circuit across the resistor 13 which is in series with the field winding 14 of the fan motor 15. When the armature 11 is pulled in by the relay 10 as described, the armature 11 moves away from the contact 12, thus 25 opening the short circuit across the resistor 13 and placing same in series with the field winding 14. This causes the speed of the motor 15 to be increased, and causes the fan to shift its operating point to the right, facing Fig. 2 of the drawing, of the dip 7 in the characteristic curve.

30 The relay 10 would be of the time delay type such as a relay having a flux decay solenoid, which would keep its armature pulled in for some time after the vane 8 has moved away from the contact 9 as a result of the fan again moving air in the right direction. By the time the armature has been released the chances are that the condition causing the fan to become unstable will have been corrected so that the controls will not 35 "hunt."

35 Each of the fans of the system preferably would be equipped with the control of Fig. 3 so that if any of the fans becomes unstable, its control will act to increase its speed.

40 While one embodiment of the invention has

2

been described for the purpose of illustration, it should be understood that the invention is not limited to the exact apparatus and system illustrated, as modifications thereof may be suggested by those skilled in the art, without departure from the essence of the invention.

5

What is claimed is:

A pressure ventilation system having a plurality of fans for directing air forwardly in parallel streams and building up an air pressure in the space supplied with air, in which due to a change in load on one of the fans, it may become unstable and move air rearwardly, means responsive to the direction of air flow through said one of said fans for maintaining same at its normal speed when the air flow through it is forward, and for

10

increasing its speed when the air flow through it is rearward, and timing means for causing said first mentioned means to maintain the increased speed for a predetermined time after the air flow is again forward.
